ABSTRACT

In an controller for effecting bumpless switching between the manual control operation and the automatic control operation there are provided an input impedance connected to receive a measured signal from a processing system, an operational amplifier to provide an output signal to a load, a transfer switch connected between the input impedance circuit and the operation amplifier, a feedback capacitor for the operational amplifier to store a voltage related to the output signal, and a manual setter including means to modify the voltage stored in the feedback capacitor by an external signal. During the automatic adjusting operation the transfer switch is operated to connect the input impedance circuit to the input terminal of the operational amplifier whereas during the control operation by the external signal the transfer switch is operated to disconnect the input impedance circuit from the operational amplifier thus modifying the voltage stored in the feedback capacitor by the signal supplied by the manual controller.

ELECTRIC CONTROLLER SYSTEMS WITH MANUAL AND AUTOMATIC MODE

BACKGROUND OF THE INVENTION

This invention relates to a novel controller utilized to control such variables in industrial processing systems as the temperature, pressure flow quantity of fluids and the like, and more particularly to a novel controller capable of controlling automatically or non-automatically.

SUMMARY OF THE INVENTION

It is an object of this invention to provide a novel controller of simple construction capable of switching its operation from automatic to manual or vice versa without the necessity of performing an balancing operation and without the trouble of bumps.

Another object of this invention is to provide an improved controller which can back-up the operation of a digital controller adapted to control a direct processing system by means of a digital operating device and can switch its operation without bumps.

Further object of this invention is to provide an controller which can limit the magnitude of an output signal supplied to a load to a predetermined constant range and can be controlled manually when desired without the necessity of manipulating a transfer switch mechanism and the like.

Still further object of this invention is to provide a novel controlling device wherein a cascade setting controlling device is comprised by a primary controller and a secondary controller and bumpless switching can be provided between cascade setting wherein the output of the primary controller is utilized as the set value of the secondary controller, and a local setting wherein the output determined by manual operation is utilized as the set value of the secondary controller.

Yet another object of this invention is to provide a new and improved cascade set controlling device whose output signal does not change rapidly when a feed forward signal is applied while feedback control is being performed or when the feedback signal is removed while both feedback control and feed forward control are being performed.

Another object of this invention is to provide a novel controlling device capable of providing bumpless switching between two or more controllers for controlling the same operating end.

Further object of this invention is to provide a novel controlling device capable of providing bumpless switching between output signals of two or more controllers where either larger or smaller outputs from these controllers is selected to supply the same operating end.

According to a preferred embodiment of this invention there is provided a controller comprising an input impedance circuit having an input terminal and an output terminal, means to apply a signal related to a measured signal from a processing system, an operational amplifier to produce an output signal supplied to a load, a transfer switch connected between the output terminal of the input impedance circuit and the input terminal of the operational amplifier, a feedback circuit including a capacitor connected between input and output terminals of the operational amplifier to store voltage related to the output signal, and a manual setter including means to modify the voltage stored in the capacitor by an external signal, the arrangement being such that at the time of the automatic control operation the transfer switch is operated to connect the output terminal of the input impedance circuit to the input terminal of the operational amplifier whereas at the time of the control operation, the transfer switch is operated to disconnect the output terminal of the input impedance circuit from the input terminal of the operational amplifier, thus modifying the voltage stored in the capacitor in the feedback circuit by the signal supplied by the manual setter.

BRIEF DESCRIPTION OF THE DRAWINGS

Further objects and advantages of this invention will become apparent from the following detailed description taken in conjunction with the accompanying drawings, in which:

FIG. 1 shows an electric connection of a basic embodiment of the novel controlling device;

FIG. 2 shows as connection diagram of a modified embodiment of this invention;

FIG. 3 shows a modification of the embodiment shown in FIG. 2 according to which the integration time and proportionality gain are multiplied by factors n_1 and n_2 respectively;

FIGS. 4 to 7 show connection diagrams of other embodiments of this invention;

FIG. 8 shows still another embodiment of this invention wherein a limiter circuit for upper and lower limits is connected to the output side of an controller;

FIG. 9A shows a limiter characteristic of a upper and lower limiter circuit having a configuration as shown in FIG. 9B;

FIG. 10A shows an input-output characteristic when the controlling device shown is FIG. 8 is controlled manually by means of a upper and lower limiter circuit;

FIG. 10B shows a perspective view of a upper and lower limiter circuit that exhibits the characteristic shown in FIG. 10A;

FIGS. 11 and 12 are connection diagrams similar to FIG. 8 but with modified upper-lower limiter circuits;

FIG. 13 shows an electrical connection of another embodiment of this invention including a source circuit;

FIGS. 14 to 16 inclusive shown connection diagrams of cascade setting controlling devices utilizing novel controllers;

FIG. 17 is a connection diagram of an automatic control apparatus utilizing the novel controller as a feed forward input;

FIGS. 18 and 19 show modifications of the automatic control apparatus shown in FIG. 17;

FIG. 20 shows a connection diagram of automatic selector controlling device wherein two or more controllers are employed and the maximum or minimum output signal of these controllers is automatically selected to control a load;

FIGS. 21A, 21B and 21C show modified automatic selecting circuits for use in the automatic selector adjusting device shown in FIG. 20;

FIG. 22 is a connection diagram of one application of this invention wherein two or more controllers are switched to control a single operating end;

FIG. 23 shows a modification of the control apparatus shown in FIG. 22 and

FIG. 24 shows another embodiment of the novel controller suitable for use in a computer wherein the set value signal is varied from time to time or for cascade control.

DESCRIPTION OF THE PREFERRED EMBODIMENTS

In the following description and claims the term "manual control" is used to mean not only a manual control with the hands of man but also an adjustment effected by an external signal from a digital computer and the like.

The embodiment of this invention shown in FIG. 1 comprises input terminals T_1 and T_2 to receive a signal ϵ related to the difference between a measured signal from a processing system and a set value or reference signal, an operational amplifier OA_1 , a capacitor C_1 and a resistor R_1 . Capacitor C_1 and resistor R_1 are connected in parallel to constitute an input impedance circuit I.I for an operational amplifier OA_1 , whereas a feedback circuit thereof is comprised by a holding capacitor C_M . A transfer switch for switching the operation between a control by an external signal and an automatic control is connected between input impedance circuit I.I and operational amplifier OA_1 . A manual setter MC is provided comprising manual switches S_1 and S_2 and sources E_1 and E_2 for manual controls. A load Lo is connected across output terminals T_3 and T_4 of operational amplifier OA_1 .

To provide the automatic control, transfer switch S_1 is thrown to a contact S_A whereby signal ϵ related to the deviation signal is applied to the input terminal of the operational amplifier OA_1 via input impedance circuit I.I. The operational amplifier operates to amplify this input signal to supply its output signal to load Lo . The output voltage Eo appearing across load Lo is fed back to the input side of the operational amplifier OA_1 via capacitor C_M so that operational amplifier OA_1 operates to reduce its input to zero. As a result, capacitor C_M stores a voltage corresponding to output voltage Eo across load Lo . When the gain of the operational amplifier OA_1 is made sufficiently large there is hold a relation expressed by equation (1) between deviation signal ϵ and the load voltage Eo

$$Eo = \epsilon \cdot \frac{C_I}{C_M} \left(1 + \frac{1}{R_I C_I S} \right)$$

$$= \epsilon \cdot K_p \cdot \left(1 + \frac{1}{T_I \cdot S} \right) \quad (1)$$

where $S : \frac{d}{dt}$

$K_p : C_I/C_M$

$T_I : R_I \cdot C_I$

As can be noted from equation (1), the device shown in FIG. 1 functions as an control which provides proportionality and integrating operations whose proportionality gain K_p is determined by C_I/C_M and integrating time T_I by $R_I C_I$.

To provide the manual control, transfer switch S_1 is thrown to contact S_M . Then one terminal of input impedance circuit I.I. is disconnected from the input terminal of operational amplifier OA_1 and connected to a point of common potential (shown as the ground) via transfer switch S_1 . The circuit comprising operational amplifier OA_1 and capacitor C_M operates as a holding amplifier to provide an output determined by the voltage stored in capacitor C_M . For this reason transfer from the automatic control to the manual control does not vary the output voltage Eo . Thus, it is possible to provide a bumpless switching from the automatic control to the manual control without the necessity of performing a balancing operation. After switching to the manual control condition in this manner, either one of manual control switches S_1 or S_D is operated to apply to operational amplifier OA_1 a positive or negative voltage from positive source E_1 or negative source E_2 via a resistor r to vary the charging voltage of capacitor C_M thus performing the manual control. More particularly, when manual control switch S_1 is closed, the output voltage Eo will increase with a time constant determined by the value of resistor r and the capacitance of capacitor C_M . Whereas when manual control switch S_D is closed the output voltage Eo will decrease with the same time constant as above described. When neither of manual control switches S_1 or S_D is closed, the charge of capacitor C_M will be held so that the output voltage Eo is maintained at a definite value. Under these manual control conditions, since one terminal of the input impedance circuit I.I. is grounded through manual-automatic transfer switch S_1 , this grounded terminal will always be maintained at the zero potential irrespective of the value of the signal ϵ related to the deviation signal. For this reason, transfer of the transfer switch S_1 from contact S_M to contact S_A to switch the condition from manual to automatic control does not cause rapid change in the output voltage Eo . Thus, it is possible to provide bumpless switching between the manual control condition and the automatic control condition without the necessity of performing a balancing operation regardless of the value of signal ϵ related to the deviation signal.

In this manner, the novel control enables bumpless switching between automatic control and manual control effected by an external signal without performing a balancing operation.

FIG. 2 shows a modified embodiment of this invention wherein a signal ϵ impressed across input terminals T_1 and T_2 75

is impressed upon one input terminal of an operational amplifier OA_1 via an input impedance circuit I.I comprising a parallel combination of a capacitor C_I and a resistor R_I and a manual-automatic transfer switch S_1 under the automatic adjustment condition. An output transistor TrO amplifies further the output signal from operational amplifier OA_1 to apply an output voltage Eo across output terminals T_3 and T_4 . The transistor also generates a current output across terminals T_5 and T_6 via current transformer CT . Output voltage Eo is fed back to the input terminal of operational amplifier OA_1 through capacitor C_M which stores a voltage corresponding to the output voltage Eo . The output signal from the manual setter MC is applied to the input terminal of operational amplifier OA_1 through resistor r . A signal P_D , consisting of a train of positive or negative pulses, for example, is impressed upon a terminal T_7 from a digital controller, not shown, and this pulse train signal P_D is applied to the input terminal of the operational amplifier OA_1 through resistor r .

The automatic and manual control operations of the embodiment shown in FIG. 2 are accomplished in the same manner as in the embodiment shown in FIG. 1. In this modification, however, to provide a back-up operation of the digital controller, the manual-automatic transfer switch S_1 is thrown to contact S_M and the back-up switch DS is closed. These switches may be comprised by transistor switching elements or relays operated synchronously with the fault of the digital controller. Thus the pulse train signal P_D from the digital controller is impressed upon the input terminal of operational amplifier OA_1 through resistor r . More particularly, as a result of application of the positive or negative pulse train signal P_D upon the input terminal of operational amplifier OA_1 , the circuit comprising this amplifier and capacitor C_M acts as a holding circuit of the integrating type to provide an analogue output voltage Eo corresponding to the pulse train signal from the digital controller across output terminals T_3 and T_4 .

At the time of the back-up operation of the digital controller, since one terminal of input impedance circuit I.I. is grounded in the same manner as the manual control operation, this grounded terminal is always maintained at zero potential irrespective of the value of signal ϵ impressed upon input terminals T_1 and T_2 . For this reason, even when the operation is switched from digital to automatic control by transferring transfer switch S_1 from contact S_M to contact S_A , the output voltage will not be varied rapidly, thus assuring bumpless switching.

FIG. 3 shows a modification of FIG. 2 wherein the integrating time and the proportionality gain are multiplied by factors n_1 and n_2 , respectively. For this purpose a potentiometer circuit comprising resistors R_1 and R_2 is connected across input terminals T_1 and T_2 and the juncture between resistors R_1 and R_2 is connected to one terminal of a resistor R_I . As a result of this connection a voltage n_1 times

$$\left(n_1 = \frac{R_2}{R_1 + R_2} \right)$$

of the signal ϵ impressed across input terminal T_1 and T_2 is applied to the input terminal of operational amplifier OA_1 via resistor R_I .

Further, a potentiometer circuit comprising resistors R_{01} and R_{02} is connected across output terminals T_3 and T_4 and the junction between resistors R_{01} and R_{02} is connected to the input terminal of operational amplifier OA_1 through capacitor C_M . With this connection $1/n_2$ times

$$\left(n_2 = \frac{R_{02}}{R_{01} + R_{02}} \right)$$

of the output voltage Eo produced across output terminals T_3 and T_4 is fed back to the input terminal of the operational amplifier OA_1 through capacitor C_M . With this embodiment it is possible to vary the integrating time at the time of the automatic control by varying the ratio of voltage division n_1 of the potentiometer circuit comprised by resistors R_1 and R_2 and to

vary the proportionality gain by varying the ratio of voltage devision n_2 of the potentiometer circuit comprised by resistors R_{01} and R_{02} .

In a modified embodiment shown in FIG. 4, there is provided a so-called differentiated anticipatory proportional, integrating and differentiating controller wherein a measured signal from the processing system is first differentiated, and then the difference signal between the differentiated signal and a reference signal is subjected to proportional and integration operations. In the embodiment, shown in FIG. 5 a measured signal e_M impressed across input terminal from the processing system is differentiated by a differential input operational amplifier OA_3 provided with a feedback circuit including a capacitor C_D and a resistor R_D and the differentiated measured signal $e_{M'}$ is applied to one input terminal of an operational amplifier OA_2 through a resistor R_{i_1} while a reference signal E_S is applied to the other input terminal of the operational amplifier OA_2 through a resistor R_{i_1} . Consequently an output signal ϵ corresponding to the difference of the differentiated measured signal $e_{M'}$ and the reference signal E_S is provided at the output terminal of operational amplifier OA_2 . A fraction of the output voltage of the operational amplifier derived from a potentiometer consisting of resistors R_{21} and R_{22} is fed back to the input terminal of operational amplifier OA_2 . Output signal ϵ from operational amplifier OA_2 is impressed upon the input terminal of operational amplifier OA_1 through input impedance circuit I.I during the automatic control operation or when manual-automatic transfer switch S_1 is thrown to contact S_4 . Whereas during the manual control operation, that is when manual-automatic transfer switch S_1 is thrown to contact S_M the output signal ϵ from operational amplifier OA_2 is coupled to the point of common potential or the ground. Capacitor C_M stores a voltage corresponding to the output current flowing through load L_0 . With this connection the relation between output voltage E_0 produced across resistor R_0 and the measured signal e_M of the processing system is expressed by the following equation (2).

$$E_0 = \left\{ \frac{1 + R_D C_D S}{1 + \frac{R_{32}}{R_{31} + R_{32}} R_D C_D S} \cdot e_M - E_S \right\} \frac{R_{2f} \cdot R_{21} + R_{22}}{R_{i_1} \cdot R_{22}}.$$

$$\frac{C_1}{C_M} \left(1 + \frac{1}{\frac{R_{11} + R_{12}}{R_{12}} C_I \cdot R_I \cdot S} \right) = \left\{ \frac{1 + R_D C_D S}{1 + \frac{1}{n} R_D C_D S} e_M - E_S \right\}$$

$$\frac{R_{2f} \cdot \alpha \frac{C_I}{C_M} \left(1 + \frac{1}{m C_I R_I S} \right)}{R_I} \quad (2)$$

where $S : \frac{d}{dt}$

$$\frac{1}{n} \cdot \frac{R_{32}}{R_{31} + R_{32}}$$

$$\alpha : \frac{R_{21} + R_{22}}{R_{22}}$$

$$m : \frac{R_{11} + R_{12}}{R_{11}}$$

As equation 2 clearly shows various constants of this modified embodiments are:

proportionality gain
integration time
integration gain
differentiation time
(measured signal alone)
differentiated gain

$$K_p = \alpha (R_{2f}) / (R_{i_1}) (C_I) / (C_M)$$

$$T_I = m C_I R_I$$

$$K_I = A_I (C_M) / (m C_I)$$

$$(A_I : \text{gain of } OA_1)$$

$$T_D = R_D C_D$$

$$K_D = n$$

Again the manual control and automatic control operations are performed in the same manner as those of the embodiment shown in FIG. 1.

FIG. 5 shows still further modification of this invention which is similar to that shown in FIG. 1 except that a pair of

diodes connected in parallel position is connected across the input terminal of the operational amplifier OA_1 and the ground. Provision of the diode circuit across the input terminal of the operational amplifier OA_1 and the ground can assure normal operation of the operational amplifier even when the output thereof becomes saturated. In this embodiment, the manual setter MC can be driven by an external signal from a digital computer or the like when switches S_1 and S_D of the manual setter MC are comprised by field effect transistor elements and by applying to these elements an upscale pulse or a down scale pulse from a digital computer, for example.

Still further embodiment shown in FIG. 6 comprises an operational amplifier OA_1 , an input impedance circuit I.I including a capacitor C_I and a variable resistor R_I , a feedback circuit for operational amplifier OA_1 comprised by capacitors C_{f_1} and C_{f_2} and a resistor R_{f_2} , potentiometer R_0 comprised by resistors R_{01} and R_{02} , a holding capacitor C_M to store a voltage corresponding to output voltage E_0 , and a manual-automatic transfer switch including interlocked movable contacts S_1 and S_2 stationary contacts S_M, S_D engageable by movable contact S_1 and S_2 at the time of the manual control or during back-up operation of a digital controller, not shown, and contacts S_A engageable by the movable contact at the time of the automatic control. These are also provided a manual setter MC comprising manual switches S_1 and S_D and sources E_1 and E_2 .

In this embodiment, to provide the automatic control, manual-automatic transfer switches S_1 and S_2 are thrown to contacts S_A . Then the juncture P_I between input impedance circuit I.I and feedback circuit F_I is connected to the input terminal of operational amplifier OA_1 via switch S_1 , whereas one terminal of capacitor C_M is grounded through switch S_2 . Then the relationship between signal ϵ impressed across input terminals T_1 and T_2 and output voltage E_0 appearing across output terminals T_3 and T_4 can be expressed by following equation (3) provided that the gain of operational amplifier OA_1 is sufficiently high.

$$40 \quad E_0 = \epsilon \cdot -\frac{C_I}{C_{f_1}} \cdot \frac{R_{01} + R_{02}}{R_{02}} \left(1 + \frac{1}{C_I R_I S} \right) \left\{ \frac{1 + R_{f_2} (C_{f_1} + C_{f_2}) S}{1 + R_{f_2} C_{f_2} S} \right\}$$

$$= \epsilon \cdot K_p \left(1 + \frac{1}{T_I \cdot S} \right) \left\{ \frac{1 + T_{D2} \cdot S}{1 + T_{D1} \cdot S} \right\} \quad (3)$$

$$45 \quad \text{where } K_p : \frac{C_I}{C_{f_1}} \cdot \frac{R_{01} + R_{02}}{R_{02}} = \frac{C_I}{C_{f_1}} \cdot \alpha$$

$$T_I : C_I R_I$$

$$T_{D1} : R_{f_2} \cdot C_{f_2} \text{ and}$$

$$T_{D2} : R_{f_2} (C_{f_1} + C_{f_2})$$

50 As can be clearly noted from equation (3) this embodiment provides a proportional, integrating and differentiating control whose proportionality constant K_p is determined by C_I/C_{f_1} , α , integrating constant T_I by $C_I R_I$, and the differentiating constants T_{D1} and T_{D2} by $R_{f_2} C_{f_2}$ and $R_{f_2} (C_{f_1} + C_{f_2})$, respectively. During the automatic control operation capacitor C_M stores the output voltage E_0 .

Upon establishment of the manual control condition by throwing manual-automatic transfer switches to their contacts S_M , the juncture P_I between input impedance circuit I.I and feedback circuit F_I is disconnected from the input terminal to operational amplifier OA_1 and grounded through switch S_2 while at the same time one terminal of capacitor C_M is connected to the input terminal of the operational amplifier OA_1 . 60 As a result, the voltage stored in condenser C_M appears across output terminals of operational amplifier OA_1 . In this manner switching from the manual control operation to the automatic control operation does not cause any appreciable variation in the output voltage, thus assuring bumpless switching.

65 To provide the manual control operation, manual switch S_1 or S_D in the manual setter MC is suitably closed to supply a different charging voltage to capacitor C_M from positive source E_1 or negative source E_2 . Denoting the closed period of manual switch S_1 or S_D by Δt , the change ΔE in the output voltage ΔE can be shown by equation (4).

$$\Delta E = -V_M/C_M \cdot r \cdot \Delta t \quad (4)$$

where V_M represents the voltages of the sources E_1 and E_2 .

Under these manual control conditions the juncture P_i between input impedance circuit I.I and feedback circuit F_i is grounded through switch S_2 . Accordingly this juncture is maintained at the zero potential to store signal ϵ impressed across input terminals T_1 and T_2 in capacitor C_i of the input impedance circuit I.I and a fraction of output voltage E_o derived from potentiometer resistors R_{01} and R_{02} in capacitor C_f of the feedback circuit F_i . For this reason, transfer of manual-automatic transfer switches S_1 and S_2 from contacts S_M to contacts S_A for switching the operation from the manual control to the automatic control does not cause rapid variation in the output voltage thus assuring bumpless switching.

To utilize the circuit shown in FIG. 6 as the output device of the digital controller, not shown, for the purpose of backing-up the same, manual-automatic transfer switches S_1 and S_2 are thrown to their contacts S_D and a positive or negative pulse train signal P_D from the digital adjusted is impressed upon the input terminal of operational amplifier OA_1 . More particularly, the positive-negative pulse train signal P_D or a positive or negative pulse signal is impressed upon the input terminal of operational amplifier via resistor r thus causing the circuit including operational amplifier OA_1 and capacitor C_M to operate as a integrating type holding circuit. In the case, where the signal from the digital control is an absolute value pulse signal or an analogue signal a resistor R_{D1} is connected in parallel with capacitor C_M to apply the signal from the digital controller to the input terminal of operational amplifier OA_1 via resistor R_{D1} thus causing the circuit including operational amplifier OA_1 and capacitor C_M to act as a holding circuit as shown in FIG. 7.

In this manner, when the circuit is operating to back-up the digital control just in the same manner as in the manual control operation, the juncture P_i between input impedance circuit I.I and feedback circuit is grounded so that this juncture P_i is always maintained at the zero potential irrespective of the value of the signal ϵ impressed across input terminals. Consequently, the switching operation from the back-up operation of the digital adjuster to the automatic control operation caused by the signal from the digital control can be effected without a bump.

In another embodiment of this invention shown in FIG. 8, the output from operational amplifier OA_1 is applied to the base electrode of an output transistor T_{ro} via a diode D_3 to obtain an output voltage E_o across a resistor R_o connected between the emitter electrode of the output transistor T_{ro} and the ground. An indicating meter ME is connected to the collector electrode to indicate the output voltage supplied to load L_o .

Between operational amplifier OA_1 and output transistor T_{ro} is connected a limiter circuit LC for upper and lower limits comprising a pair of transistors T_{rl} and T_{rh} and a variable resistor R_v provided with two sliding brushes B_H and B_L . The limiter circuit being constructed such that transistor T_{rl} becomes ON when the output voltage of operational amplifier OA_1 becomes smaller than a lower limit voltage e_L established by brush B_L whereas transistor T_{rh} becomes ON when the output voltage of the operational amplifier OA_1 becomes larger than the upper limit voltage e_H established by brush B_H . As a result the operating characteristics of limiter circuit LC is shown by the graph of FIG. 9A, which shows that the output voltage E_o varies linearly in the range between the lower set voltage e_L and the upper set voltage e_H of the output voltage E_o from the operational amplifier OA_1 . The limiter circuit LC has an appearance as shown in FIG. 9B. Thus, set arms or reference markings S_H and S_L for upper and lower limits and respectively connected to brushes B_H and B_L are pivotally mounted on a shaft to cooperate with the dial of indicating meter ME . Upper and lower limit voltages V_H and V_L can be varied by adjusting the position of these arms S_H and S_L .

Provision of such a limiter circuit LC enables to maintain the output voltage E_o always in a constant range even when

the output voltage e_o of operational amplifier OA_1 deviates from said range. In an arrangement where the voltage stored in capacitor C_M is held to provide the output under the manual control condition as shown in FIG. 1 the voltage of capacitor C_M tends to gradually decrease due to leakage so that such arrangement can not provide the manual control operation over a long period of time. Whereas, where limiter circuit LC is incorporated as in the embodiment shown in FIG. 8 the output voltage E_o will never become lesser than the lower limit value e_L , thus enabling manual control over a long period of time.

Further, in this embodiment, by selecting substantially the same values for the upper and lower limit set voltage e_H and e_L and by making both of them variable, the output voltage E_o can be varied accordingly. More particularly, when the upper and lower limit set voltage e_H and e_L are selected to be substantially the same, the operating characteristics of the limiter circuit LC will become to that shown in FIG. 10A so that by simultaneously varying the upper and lower limit set voltage e_H and e_L in the direction of arrow a or b , the output voltage E_o is also varied in the direction of arrow c or d . Accordingly, as shown in FIG. 10 by aligning set markings S_H and S_L for upper and lower limits and by adjusting them in unison while observing the indication of the indicating meter ME , manual control can also be made. Under such manual control condition wherein the upper and lower limit voltage e_H and e_L are varied in unison, since capacitor C_M stores the voltage corresponding to the output voltage E_o applied to load L_o it is possible to transfer the operation from the manual control to the automatic control without bumps.

FIGS. 11 and 12 show connection diagrams of still further embodiments of this invention utilizing different limiter circuits LC from that shown in FIG. 8.

The limiter circuit LC shown in FIG. 11 comprises three transistors T_{rl} , T_{rh} and T_{ro} , and a variable resistor R_v including two brushes B_H and B_L . In this embodiment, when output voltage e_o from operational amplifier OA_1 becomes less than the lower limit set voltage e_L established by brush B_L transistor T_{rl} is rendered OFF to increase the base potential of transistor T_{rh} thus rendering conductive transistor T_{rh} . On the other hand, when output voltage e_o of operational amplifier OA_1 increases beyond the upper limit set voltage e_H established by brush B_H transistor T_{rh} is rendered conductive. In this manner, the output voltage E_o is maintained in a definite range defined by upper and lower limit set voltage e_H and e_L .

The limiter circuit LC shown in FIG. 12 comprises a variable resistor R_v having two brushes B_H AND B_L , a first comparator Co_H for comparing the output voltage E_o with voltage e_H established by brush B_H and a second comparator Co_L for comparing output voltage E_o with voltage e_L established by brush B_L and diodes D_H and D_L which are controlled to their ON and OFF states by the outputs from comparators Co_H and Co_L . When output voltage e_o from operational amplifier OA_1 becomes less than the lower limit set voltage e_L , comparator Co_L causes diode D_L to become ON. On the other hand, when output voltage e_o from operational amplifier OA_1 becomes larger than the upper limit set voltage e_H comparator Co_H causes diode D_H to become ON. In this manner, output voltage E_o is maintained in a safe range defined by upper and lower limit set voltages e_H and e_L .

FIG. 13 shows a connection diagram of another embodiment of the novel control including the source circuit. Where an operational amplifier is comprised by a linear integrated circuit and the like, although it is usual to provide positive and negative sources of supply to operate the amplifier, this embodiment utilizes a single DC source. In this embodiment, a power source PS supplying DC 24 volts is connected to serially connected resistor R_p and Zenor diode D_z to produce a bias voltage $E_B = 10$ volts at the juncture between resistor R_p and Zenor diode D_z . Source terminals of operational amplifiers OA_1 , OA_2 and OA_3 are respectively connected to a zero volt line l_0 and 24 volt line l_{24} connected to power source PS. A measured signal e_M from a processing system, not shown, is supplied across one input terminal T_{11} of operational

amplifier OA_3 and a common signal line 1_{SC} while a reference or set value signal E_S across the other input terminal T_{12} of operational amplifier OA_3 and common signal line 1_{SC} . Thus, operational amplifier OA_3 functions to amplify the difference between measured signal e_M from the processing system and reference signal E_S to produce at its output a deviation signal ϵ biased by bias voltage E_B and expressed by an equation $\epsilon = E_B + R_f/R_i (e_M - E_S)$. Since the input voltage to the operational amplifier is expressed by

$$\frac{e_M R_f' + E_B R_i'}{R_i' + R_f'},$$

by the suitable selection of values of bias voltage E_B , and resistors R_i' and R_f' , operation of the operational amplifier OA_3 in the most suitable operational range can be assured. The deviation signal ϵ is subjected to proportional and differentiating operations by means of a circuit including resistor R_D and capacitor C_D and thence imparted with a proportionality gain by means of a circuit including resistors R_{21} and R_{22} . Since these operations are performed by taking the bias line 1_B at the reference potential E_B as the reference these operations are performed only for the term $R_f/R_i (e_M - E_S)$ of the deviation signal ϵ and not for the bias voltage E_B . Output signal from the operational amplifier is subjected to proportional and integrating operations by means of an input impedance circuit comprising capacitor C_I , resistor R_I , and resistors R_{11} and R_{12} and of a circuit including capacitor C_M and operational amplifier OA_1 to obtain output voltage E_{01} . Since this output voltage E_{01} utilizes the voltage of bias line 1_B at the reference voltage the output signal is shifted by the circuit comprising transistor Tr_{03} and Tr_{02} to provide a current output signal I_0 and a voltage output signal E_0 at output terminals T_3 and T_4 , said output signals I_0 and E_0 utilizing the voltages of zero volt line 1_0 and common signal line 1_{SC} as the references. The output voltage E_{01} of this controller is expressed by equation (5).

$$E_{01} = \frac{R_f}{R_i} \cdot \frac{1}{n} \cdot \alpha \cdot \frac{1+n \cdot R_D C_D S}{1+R_D C_D S} \cdot \frac{C_I}{C_M} \left(1 + \frac{1}{m \cdot C_I R_I S} \right) (e_M - E_S) \quad (5)$$

where $\frac{1}{n} = \frac{R_{32}}{R_{31} + R_{32}}$

$$\frac{1}{\alpha} = \frac{R_{21}}{R_{21} + R_{22}} \text{ and}$$

$$\frac{1}{m} = \frac{R_{12}}{R_{11} + R_{12}}$$

In this embodiment, however, since the zero volt line of the source and the zero volt line of the signal are comprised by a signal common line there is a fear that the voltage drop caused by the source current might cause an error of the signal. To avoid this it is advantageous to separate zero volt line 1_0 and common signal line 1_{SC} as shown in FIG. 13 and connect them to the source at a point in the system.

FIGS. 14 through 16 illustrate connection diagrams of cascade setting controlling devices or circuits utilizing the novel controller.

The cascade setting controlling device comprises a primary controller and a secondary controller with the output from the primary controller utilized as the set value of the secondary controller, such controller device being frequently used where the control loop of the primary controller involves a large delay. In such a cascade setting controller device, in addition to providing control by the cascade setting it is constructed such that it can also provide a control by the so-called local setting in which a manually controlled output is utilized at the set value of the secondary controller.

In each of the embodiments shown in FIGS. 14 through 16 the switching operation between the cascade setting and the local setting can be made without bumps. The embodiment shown in FIG. 14 comprises a primary controller C_1 and a secondary controller C_2 which are of substantially the same

construction providing proportionating and integrating operations. The operational amplifier OA_2 of the primary controller C_1 operates to amplify the difference between a measured signal e_M from a processing system, not shown, and a reference value E_{S1} to apply its output to one terminal of an input impedance circuit $I.I$ including capacitor C_I and resistor R_I , and a portion of the output voltage derived from a potentiometer comprised by resistors R_{21} and R_{22} that determine the proportionality constant is negatively fed back to one input terminal of operational amplifier OA_2 through feedback resistor R_{2f} . A cascade-local transfer switch S_3 adapted to transfer between cascade setting and local setting is thrown to contact SC during the cascade setting operation to couple the output from operational amplifier OA_2 to the input terminal of operational amplifier OA_1 via input impedance circuit $I.I$ whereas during local setting transfer switch S_3 is thrown to contact S_1 to ground the output from operational amplifier OA_2 through input impedance circuit $I.I$. The output from operational amplifier OA_1 , that is the output from the primary controller C_1 is impressed upon one input terminal of the operational amplifier OA_2 of the secondary controller as the set value or reference signal therefore, and is also fed back to the input terminal of operational amplifier OA_1 through capacitor C_M . Consequently, capacitor C_M stores the output signal from the primary controller C_1 , that is the set value signal of the secondary controller C_2 . A local setter LS comprises local setting switches S_1 and S_2 and local setting sources E_1 and E_2 , and the output from local setter LS is connected to the input terminal

- 10 of operational amplifier OA_1 through resistor r . The relationship between input signal e_{M1} and output voltage E_{S2} of the primary controller C_1 described above can be shown by following equation (6)
- 15
- 20
- 25
- 30
- 35

$$E_{S2} = (e_{M1} - E_{S1}) \frac{R_{2f}}{R_i} \cdot \frac{R_{21} + R_{22}}{R_{22}} \cdot \frac{C_I}{C_M} \left(1 + \frac{1}{C_I R_I S} \right) \quad (6)$$

- In the secondary adjusted C_2 , operational amplifier OA_2 operates to amplify the difference between measured signal e_{M2} from the processing system and the output signal from the primary controller C_1 to apply its output to one end of the input impedance circuit $I.I$ including capacitor C_I and resistor R_I . A fraction of this output voltage derived from potentiometer resistors R_{21} and R_{22} which determine the proportionality constant is negatively fed back to the input terminal of operational amplifier OA_2 through resistor R_{2f} . Manual-automatic transfer switch S_1 for switching the operation between the automatic control and the manual control is thrown to contact S_M during the automatic control operation to ground the output from the operational amplifier OA_1 via input impedance circuit $I.I$. Whereas during the automatic adjustment operation the transfer switch S_1 is thrown to contact S_A to connect the output from operational amplifier OA_2 to the input terminal of operational amplifier OA_1 via input impedance circuit $I.I$. The output from operational amplifier OA_1 is amplified by output transistor Tr_0 to produce output voltage E_0 across output terminals T_3 and T_4 . A current output is obtained from output terminals T_5 and T_6 through current transformer C_7 . Since output voltage E_0 is fed back to the input terminal of operational amplifier OA_1 through capacitor C_M this capacitor stores a voltage corresponding to output voltage E_0 . As shown, the output terminal of manual setter MC is connected to the input terminal of operational amplifier OA_1 through resistor r .

- 60
- 65
- 70
- 75
- The embodiment shown in FIG. 14 operates as follows: To perform a control determined by the cascade setting, cascade-local transfer switch S_3 in the primary controller C_1 is thrown to contact SC , while manual-automatic transfer switch S_1 in the secondary controller to contact S_A . Under these conditions the set value of the secondary controller C_2 is set by the output from the primary controller C_1 utilizing the measured signal e_{M1} as its input signal. In other words, the output signal from the primary controller C_1 is directly used as the set value signal E_{S2} of the secondary controller C_2 . Consequently, output volt-

age E_o under this cascade control condition is given by following equation (7).

$$E_o = (e_{M2} - E_{S2}) \frac{R_{2f}}{R_f} \cdot \frac{R_{21} + R_{22}}{R_{22}} \cdot \frac{C_f}{C_M} \left(1 + \frac{1}{C_f R_f S} \right) \quad (7)$$

To switch the operation from this control by the cascade setting to the control by local setting, the cascade-local transfer switch S_3 of the primary controller C_1 is thrown to contact S_L . Then the circuit comprising operational amplifier OA_1 of the primary controller C_1 and capacitor C_M will act as a holding amplifier to produce an output corresponding to the voltage which has been stored in capacitor C_M . Since capacitor C_M has been storing the output voltage of operational amplifier immediately prior to the switching of transfer switch S_3 or the set voltage E_{S2} of the secondary controller C_2 it is possible to switch from the control by the cascade setting to the control by the local setting without bumps.

The control by the local setting can be effected by suitably closing either one of local setting switches of local setter LS while observing the reading of indicating meter ML that indicates set value signal E_{S2} of the secondary controller C_2 , thus varying the charging voltage for capacitor C_M . Under this control condition by the local setting, since one terminal of input impedance circuit I.I of the primary controller C_1 is grounded through transfer switch S_3 , this grounded terminal is kept at the zero potential irrespective of the value of the input deviation signal. For this reason, even when the operation is transferred from the control by the local setting to the control by the cascade setting by transferring the transfer switch S_3 of the transfer switch S_3 of the primary controller from contact S_L to contact S_C there is no fear of bumps.

In this embodiment, to provide the manual control operation, the manual-automatic transfer switch S_1 of the secondary controller C_2 is thrown to contact S_M , and either one of manual controlling switches S_1 or S_D of manual setter MC is suitably closed thus varying the charging voltage for capacitor C_M of the secondary controller C_2 .

Although in this embodiment, both primary and secondary controllers have been shown as being comprised by proportional and integrating controllers it will be understood that they may be comprised by proportional, integrating and differentiating controllers.

FIGS. 15 is a connection diagram of still another example of the cascade setting control device. In this embodiment local setter LS comprises a voltage generating circuit PM wherein the voltage generated by a brush 12 is varied by moving the brush by a local set value adjusting knob 11, cascade-local transfer switches S_{31} and S_{32} for switching between the cascade setting and the local setting, an operational amplifier OA_3 and a balancing motor BM driven by the output from operational amplifier OA_3 to move brush 12 of the voltage generator PM. In this local setter LS, to perform the control by the cascade setting, transfer switches S_{31} and S_{32} are thrown to their contacts S_C to constitute a servo circuit by operational amplifier OA_3 , balancing motor BM and voltage generator PM thus causing the local setter LS to act as an indicating meter wherein the output E_{S2} from the primary controller C_1 is indicated by the position of brush 12. Further to effect the control by the local setting, transfer switches S_{31} and S_{32} are thrown to their contacts S_L . Then, as the balancing motor BM is disconnected from the output terminal of operational amplifier OA_3 the brush 12 of voltage generator PM will maintain the output signal E_{S2} from the primary controller C_1 immediately before transfer of transfer switches S_{31} and S_{32} , and a circuit is constructed utilizing the voltage maintained at brush 12 as the set value signal for the secondary controller C_2 . Thus, it is possible to switch from the control by the cascade setting to the control by the local setting without bumps. The control effected by the local setting may be performed by controlling the local set value adjusting knob 11 to vary the voltage E_{S2} generated by voltage generator PM. Since at this time, one terminal of capacitor C_M of the primary

controller C_1 is grounded through switch S_3 , this capacitor C_M stores voltage E_{S2}' generated by voltage generator PM of local setter LS. One end of the input impedance circuit comprising capacitor C_f and resistor R_f of the primary controller C_1 is also grounded through switch S_3 , so that this end is maintained at the zero potential regardless the value of input signal e_{M1} . As a result, it is possible to switch the operation from the control by the local setting to the control by the cascade setting without bumps by throwing switch S_3 of the primary controller C_1 and switches S_{31} and S_{32} of the local setter to their contacts S_C .

FIG. 16 shows still another example of the cascade setting controlling device embodying this invention. In this embodiment, the local setter LS comprises a voltage generating circuit PM wherein the voltage generated at brush 12 is varied by moving the brush by means of a local set value adjusting knob 11. An indicating meter ML is connected between the output terminal of operational amplifier OA_1 of the primary controller C_1 and the common line to indicate the output signal from the primary controller C_1 . With this embodiment, to effect the control by the cascade setting the switch S_3 of the primary controller C_1 is thrown to contact S_C whereas in the local setter LS, switch S_{31} is thrown to contact S_C (it is assumed now that the switch S_1 of the secondary controller C_2 is engaging contact S_A). Under these circumstances, the set value of the secondary controller C_2 is set by the output from the primary controller C_1 utilizing the measured signal e_{M1} from the processing system as its input signal. In other words, the output from the primary controller C_1 is directly used as the set value of the secondary controller.

To switch the operation from the control by the cascade setting to the control by the local setting switch S_3 of the primary controller C_1 is thrown to its contact S_L while at the same time switch S_{31} of local setter LS is thrown to contact S_L . Then one end of the input impedance circuit of the primary controller C_1 is grounded and one input to the operational amplifier OA_1 and one terminal of capacitor C_M are also grounded. In the local setter LS, its output voltage E_{S2}' charge or discharges capacitor C_M of the primary controller and the output voltage is also applied to the secondary controller C_2 as its set value input. In this manner, the control by local setter LS can be provided by adjusting the voltage E_{S2}' generated by voltage generator PM by controlling the local set value adjusting knob while observing the indication of meter ML. If, prior to the transfer of switches S_3 and S_{31} from contacts to contacts S_L , the output voltage E_{S2}' of the local setter LS were controlled to be equal to the output voltage from the primary controller C_1 , such switching could be made without bumps. During control by the local setting, since one terminal of capacitor C_M of the primary controller C_1 is grounded, this capacitor stores the output voltage E_{S2}' from local setter LS. Further, as one terminal of the input impedance circuit of the primary controller C_1 is grounded through switch S_3 , this grounded terminal is also maintained at the zero potential irrespective of the value of input signal e_{M1} . As a result, the switching operation from the control by the local setting to the control by the cascade setting effected by connecting switch S_3 of the primary controller C_1 to contact S_C and switch S_{31} of the local setter LS to contact S_{C1} can be made without bumps.

FIG. 17 shows a connection diagram of the novel controller as applied to an automatic control device including a feed forward input. The control device comprises a feedback controller C_1 and a feed forward signal generating circuit C_2 . Feedback controller C_1 comprises input terminals T_1 and T_2 for receiving a feedback input signal e_{M1} from the processing system, not shown, a source of reference signal E_{S1} , an operational amplifier OA_2 and resistors R_{21} and R_{22} for controlling the proportionality gain the operational amplifier OA_2 functions to amplify the difference between input signal e_{M1} and the reference signal E_{S1} . Again the input impedance circuit I.I is comprised by a capacitor C_1 and a variable resistor. The control device further comprises a manual-automatic transfer switch S_1 for switching the operation between the manual control and the automatic control, an operational amplifier OA_1 ,

a capacitor C_M to store a voltage corresponding to output voltage E_0 supplied to the load, the capacitor C_M also serving as the feedback circuit for the operational amplifier OA_1 . The output terminal of manual setter MC is connected to one input of the operational amplifier OA_1 via a resistor r .

The feed forward signal generating circuit C_2 comprises input terminals T_6 and T_7 for receiving external disturbance signals, an operational amplifier OA_3 , a resistor R_1 , and a capacitor C_1 , these last mentioned two elements comprising an input impedance circuit I.I for operational amplifier OA_3 . The feed forward signal generating circuit further comprises resistors R_{21} and R_{22} for controlling the proportionality gain and a feedback circuit for the operational amplifier OA_3 comprised by a resistor R_{22} and a capacitor C_{22} . The feed forward signal generated by feed forward signal generating circuit C_2 is coupled to one terminal of the input impedance circuit I.I of feedback controller C_1 via a capacitor C_{C1} and a switch S_{33} .

The automatic control device shown in FIG. 17 operates as follows: To provide a normal feedback control, manual-automatic transfer switch S_1 is thrown to contact S_A and switch S_{33} to contact S_F . Then the output from the feed forward signal generating circuit C_2 is grounded through contact S_F of switch S_{33} . In the feedback controller C_1 , the input impedance circuit I.I is connected to the input terminal of operational amplifier OA_1 through manual-automatic transfer switch S_1 so that a different signal between input signal e_{M1} and a reference signal E_{S1} is applied to the input terminal of operational amplifier OA_1 via input impedance circuit I.I. Under these conditions, the control device operates in the same manner as the basic controller shown in FIG. 1. Since, at this time, one terminal of capacitor C_{C1} which is connected to the output terminal of the feed forward signal generating circuit C_2 is grounded through switch S_{33} , this grounded terminal is always maintained at the ground potential irrespective of the value of the external disturbance signal.

During this feedback control operation, in order to apply feed forward signal e_{M2} , switch S_{33} is thrown to contact S_N . Then the feed forward signal e_{M2} from feed forward signal generating circuit C_2 is applied to the input terminal (the point of addition) of operational amplifier OA_1 via capacitor C_{C1} and switch S_{33} . The output voltage under these conditions is given by following equation (8)

$$E_0 = (e_{M1} - E_{S1}) \frac{R_{21} + R_{22}}{R_{22}} \cdot \frac{C_1}{C_M} \left(1 + \frac{1}{C_1 R_1 S} \right) + e_{M2} \frac{C_{C1}}{C_M} GF(s) \quad (8)$$

where $GF(s)$ represents the transfer function of the feed forward signal generating circuit C_2 .

At the moment when switch S_{33} is transferred from contact S_F to contact S_N , one terminal of capacitor C_{C1} and the input terminal (the point of addition) of the operational amplifier OA_1 are maintained at the zero potential so that when switch S_{33} is transferred as above described to perform the feedback control, even when both feedback control and the feed forward control are used, the output voltage E_0 does not vary at that moment.

Where both feedback control and feed forward control are used as above described a voltage corresponding to output voltage E_0 is stored in capacitor C_M , removal of feed forward signal e_{M2} caused by the connection of switch S_{33} with contact S_F does not cause any rapid variation in the output voltage E_0 .

In this control device, the transfer function of the feed forward signal generating circuit C_2 is suitably modified according to the field of application of the control system.

FIG. 18 shows a connection diagram of a modification of the control device shown in FIG. 17. The feed forward signal generating circuit C_2 of this modification comprises an operational amplifier OA_3 wherein when the external disturbance signal e_{M2} is impressed upon one input terminal of the operational amplifier the output signal e_{M1} of operational amplifier OA_2 of the feedback controller C_1 is impressed upon the other input terminal, and resistors R_1 and R_{22} .

The input impedance circuit of this control device is comprised by a resistor R_{11} and a capacitor C_1 and the output

signal e_{M1} from the operational amplifier OA_2 of the feed forward controller C_1 is given by following equation (9).

$$e_{M1} = \frac{R_{21} + R_{22}}{R_{22}} (e_{M1} - E_{S1}) \quad (9)$$

Operation amplifier OA_3 of the feed forward signal generating circuit C_2 operates to add (or subtract) the external disturbance signal e_{M2} and the output signal e_{M1} of operational amplifier OA_2 expressed by equation (8), so that the output signal e_{M2} of the operational amplifier OA_3 is given by

$$e_{M2} = e_{M1} - e_{M2}$$

$$= - \frac{R_{21} + R_{22}}{R_{22}} (e_{M1} - E_{S1}) - e_{M2} \quad (10)$$

Under the automatic control condition in which manual-automatic transfer switch S_1 engages contact S_A , the output signal of operation amplifier OA_2 given by equation (8) is applied to the input terminal of operational amplifier OA_1 while feed forward signal e_{M2} given by equation (9) is impressed upon the same input terminal via capacitor C_1 so that with a sufficiently high gain of the operational amplifier OA_1 , the output voltage E_0 is given by equation (11).

$$E_0 = -e_{M1} \cdot \frac{1}{C_M R_{11} S} - e_{M2} \frac{C_1}{C_M}$$

$$= - \frac{R_{21} + R_{22}}{R_{22}} (e_{M1} - E_{S1}) \cdot \frac{1}{C_M R_{11} S}$$

$$+ \frac{C_1}{C_M} \left\{ \frac{R_{21} + R_{22}}{R_{22}} (e_{M1} - E_{S1}) + e_{M2} \right\}$$

$$= n \cdot \frac{C_{11}}{C_M} \left(1 + \frac{1}{C_{11} R_1 S} \right) (e_{M1} - E_{S1}) + \frac{C_{11}}{C_M} \cdot e_{M2} + \frac{C_{11}}{C_M} \cdot e_{M2} \quad (11)$$

As can be clearly noted from equation (11), this control device performs proportional and integrating operations upon the difference signal between input signal e_{M1} and reference signal E_{S1} , with a proportionality gain C_{11}/C_M and an integrating constant $C_{11} R_1$. For the external disturbance signal e_{M2} the control device performs proportionating and integrating operations with the proportionality gain C_{11}/C_M .

FIG. 19 shows a connection diagram of still further modification of the control device shown in FIG. 17. In a processing system for controlling the combustion condition of a large boiler, for example, as the quantity of air fed to the boiler is large it is often necessary to provide two or more values (the load of the control system) for controlling the air quantity. The embodiment shown in FIG. 19 is suitable to control such a processing system. The control device shown in this figure comprises an operator section I connected to receive a measured signal e_{M1} from the processing system, a feed forward signal generating circuit connected to receive the external disturbance signal e_{M2} and the output signal e_{M1} of the operator I via resistor R_{12} , an output section III including a manual setter MC_1 to provide an output signal for load L_{01} and a second output section having a manual setter MC_2 to provide an output signal to another load L_{02} .

Operator section I, feed forward signal generating circuit II and output section III₁ cooperate to constitute a control device for driving load L_{01} while operator section I, feed forward signal generating circuit II and output section III₂ cooperate to constitute a control device for driving load L_{02} . Thus, with this control device it is possible to control automatically both loads L_{01} and L_{02} just in the same manner. Where it is desired to manually control load L_{01} alone, manual-automatic transfer switch S_1 of the output section III₁ is transferred from contact S_A to contact S_M and either one of the switches S_1 or S_D of manual setter MC_1 is suitably closed. More particularly, when transfer switch S_1 of the output sec-

tion III₁ is thrown to contact S_M, operational amplifier OA₁ operates as a holding amplifier to utilize the voltage which has been stored in capacitor C_{M1} as the output so that it is possible to manually control only load L_{o1} by closing either one of the switches S₁ or S_D of manual setter MC₁ to vary the charging voltage for capacitor C_{M1}. Under this manual control condition of load L_{o1} since one terminal of capacitor C_I comprising the input impedance circuit of the output section III₁ is grounded through transfer switch S₁ this capacitor stores the output voltage E_{M2} of feed forward signal generating circuit II. As a result, by increasing the value of resistor R_I comprising the input impedance circuit, transfer operation from the automatic control to the manual control in the output section III₁ does not affect in any way the automatic control operation in the output section III₂.

According to this control system it is possible to provide identical automatic control for two or more loads by utilizing the measured signal e_{M1} from the processing system and the external disturbance signal e_{M2} as the input signals. Further, during the manual control operation it is possible to manually control only the desired load without affecting the other load.

FIG. 20 illustrates an electrical connection diagram of the novel control as applied to an automatic selector adjuster device wherein two or more controllers are employed and the largest or smallest output signal among the output signals from these plurality of controllers is selected automatically to control a single load. This system is suitable to automatically control the controlled quantity of the processing system to prevent it from exceeding a certain upper limit (or decreasing below a lower limit) in order to assure safety operation of the plant.

In the illustrated embodiment, two controllers C₁ and C₂ are used and larger one of the output signals from these controllers is selected automatically and applied to the load. In this embodiment, controller C₁ utilizes the measured signal e_{M1} from the processing system as its input signal whereas controller C₂ utilizes the measured signal e_{M2} from the processing system as its input signal. Controllers C₁ and C₂ have substantially the same circuit construction. Output terminal of controller C₁ (that is the output terminal of operational amplifier OA₁) is connected to the base electrode of output transistor T_{ro} through a diode DA₁ while the output terminal of controller C₂ (that is the output terminal of operational amplifier OA₁) is connected to the base electrode of output transistor T_{ro} through another diode DA₂. Diodes DA₁ and DA₂ constitute an automatic selector circuit AS. One terminal of each capacitor C_{M1} and C_{M2} of controllers C₁ and C₂ is connected to one terminal of a load resistor R_o, so that each capacitor stores a voltage corresponding to the output voltage E_o.

Assuming now that the output signal e_{o1} from controller C₁ is larger than the output signal e_{o2} from controller C₂, then diode DA₁ of the automatic selector circuit AS becomes conductive state and diode DA₂ is held non-conductive state. As a result output signal e_{o1} from controller C₁ is applied to the base electrode of output transistor T_{ro} to supply an output current to load L_o and output load resistor R_o corresponding to the output signal e_{o1}. Under these circumstances a voltage corresponding to the output signal e_{o1} from controller C₁ is stored in capacitors C_{M1} and C_{M2} of controller C₁ and C₂, respectively.

If output signal e_{o2} of controller C₂ increases to a value larger than the output signal e_{o1} from controller C₁ then diode DA₂ will become conductive whereas diode DA₁ non-conductive. As a result, an output current I_o corresponding to the output signal e_{o2} of controller C₂ flows through the load L_o and a voltage corresponding to output signal e_{o2} is stored in capacitors C_{M1} and C_{M2} of controller C₁ and C₂, respectively.

Considering now the moment at which the signal supplied to the load L_o is switched from the output of controller C₁ to that of controller C₂, these two output signals may become equal at that moment so that the capacitors C_{M1} and C_{M2} of controller C₁ and C₂, respectively store the same voltage. Thus the switching from controller C₁ to adjuster C₂ or vice versa is effected automatically without bumps.

FIG. 21A shows a modification of the automatic selector circuit AS shown in FIG. 20. Fore particularly, in the circuit shown in FIG. 21A diodes DA₁ and DA₂ in FIG. 20 are replaced by transistors T_{D1} and T_{D2} to construct the automatic maximum selector circuit AS for selecting larger one of the output signals from controller C₁ and C₂.

In another modification shown in FIG. 21B, the polarity of diodes DA₁ and DA₂ is reversed from that of the diodes shown in FIG. 20 and a source of positive polarity is connected to the anode electrodes of these diodes via resistor R_{AS} so as to automatically select the smaller one of the output signals from controller C₁ and C₂ thus constituting a selector circuit AS for automatically selecting the minimum value.

In another selector circuit AS for automatically selecting the minimum value shown in FIG. 21C diodes DA₁ and DA₂ shown in FIG. 21B are substituted by transistors T_{D1} and T_{D2}, respectively.

FIG. 22 shows a connection diagram of the novel controller applied to a control device wherein two or more controllers are switched to control the same operating end. In this embodiment, controller C₁ utilizes the measured signal e_{M1} from the processing system as its input signal whereas controller C₂ utilizes the measured signal e_{M2} from the processing system as its input signal. The output terminal of controller C₁ and that of controller C₂ are selectively connected to the base electrode of output transistor T_{ro} by means of a transfer switch S_{3D}. One end of each capacitor C_{M1} and C_{M2} of controllers C₁ and C₂, respectively, are connected to one terminal of output load resistor R_o, each of said capacitors storing a voltage corresponding to output voltage E_o. It is to be understood that transfer switch S_{3D} is interlocked with switches S₃₁ and S₃₂ adapted to connect one ends of capacitors C_{M1} and C_{M2} to the ground.

Where it is desired to control load L_o in accordance with the output signal from controller C₁ transfer switch S_{3D} is thrown to contact S_{C1} and both switches S₃₁ and S₃₂ to their contacts S_{C1}. Then the output e_{o1} of controller C₁ (that is the output of operational amplifier OA₁) is applied to the base electrodes of output transistor T_{ro} to apply output voltage E_o across output load resistor R_o. The output voltage E_o is negatively fed back to the input terminal of operational amplifier OA₁ via capacitor C_{M1}. By selecting a sufficiently large gain for the operational amplifier OA₁, the output voltage E_o can be expressed by equation (12).

$$E_o = (e_{M1} + E_{S1}) \frac{R_{21} + R_{22}}{R_{22}} \cdot \frac{C_I}{C_{M1}} \left(1 + \frac{1}{C_I R_o S} \right) \quad (12)$$

At this time the input terminal of operational amplifier OA₁ is maintained at the zero potential to store a voltage corresponding to output voltage E_o in capacitor C_{M1}. Since one terminal of capacitor C_{M2} of controller C₂ is applied with output voltage E_o and the other terminal of the capacitor (that is the input terminal of operational amplifier OA₁) is grounded and maintained at the zero potential capacitor C_{M2} also stores the voltage corresponding to output voltage E_o.

Accordingly as the transfer switch S_{3D} is thrown to contact S_{C2} from contact S_{C1} so as to control load L_o by the output signal e_{o2} from operational amplifier OA₁ of controller C₂, the circuit comprising this operational amplifier and capacitor C_{M2} functions as a holding amplifier to supply the voltage which has been stored in capacitor C_{M2} as the output voltage. In this manner, it is possible to switch the control of output voltage from controller C₁ to controller C₂ without accompanying rapid variation or bump.

The automatic control operation by controller C₂ can be made in exactly the same manner as by controller C₁. Since, at this time, capacitor C_{M2} of controller C₂ and capacitor C_{M1} of controller C_{M1} store the voltage corresponding to the output voltage E_o, transfer of the operation from controller C₂ to controller C₁ can also be made without bumps.

FIG. 23 shows a modification of the circuit shown in FIG. 22. The control circuit shown in FIG. 23 comprises a first operator section I utilizing the measured signal e_{M1} from the

processing system as its input signal, a second operator section II utilizing the measured signal e_{M2} from the processing system at the input signal, and an output section III including a pair of input impedance circuits II_1 and II_2 , transfer switches S_{11} , S_{12} and S_{13} , an operational amplifier OA_2 and a capacitor C_M , said output section III supplying an output signal to load L_o . Transfer switches S_{11} , S_{12} and S_{13} are interlocked with each other and are interposed between the operational amplifier OA_1 and its input impedance circuits II_1 and II_2 . These switches are operated to perform the control by operating section I, the manual control by manual setter MC or the control by the operator section II.

When it is desired to control load L_o by the measured signal e_{M1} transfer switches S_1 , S_2 and S_3 are thrown to contacts SA_1 , respectively. Then, the deviation signal ϵ_1 from operator section I is applied to the input terminal of operational amplifier OA_1 in the output section III through capacitor C_{11} of input impedance circuit II_1 . Further, a portion (signal ϵ'_1) of deviation signal derived from potentiometer resistors R_{31} and R_{32} is impressed upon the input terminal of operational amplifier OA_3 via resistor R_{11} . In this manner, operator section I and output section III cooperate to constitute a first controller which utilizes the measured signal e_{M1} as the input signal. The output voltage E_o thus obtained is given by following equation (13).

$$e_o = (e_{M1} - E_{S1}) \cdot \frac{R_{21} + R_{22}}{R_{22}} \cdot \frac{C_{11}}{C_M} \left\{ 1 + \frac{1}{\frac{R_{31} + R_{32}}{R_{32}} C_{11} R_{11} S} \right\} \quad (13)$$

Under these circumstances the input terminal of operational amplifier OA_1 is maintained at the zero potential to store a voltage corresponding to output voltage E_o in capacitor C_M in the feedback circuit for the operational amplifier OA_1 . One terminal of capacitor C_{12} of the second input impedance circuit II_2 is maintained at the zero potential since it is grounded through transfer switch S_{13} , whereby the capacitor C_{12} stores the deviation signal ϵ_2 from operator section II. As a result, even when transfer switches S_1 , S_2 and S_3 are transferred from their contacts SA_1 to contact SA_2 the circuit comprising operational amplifier OA_1 and capacitor C_M functions as a holding amplifier which provides the voltage stored in capacitor C_M as the output. For this reason, output voltage E_o does not vary at all, so that it is possible to transfer the operation from the control by the deviation signal ϵ_1 from operator section I to the control by the deviation signal ϵ_2 from operator section II without bumps.

To utilize this embodiment as an automatic controller, transfer switches S_1 , S_2 and S_3 are thrown to their contacts SA_2 , respectively, and either one of the manual switches S_1 and S_2 of the automatic setter MC is suitably closed to vary the charging voltage for capacitor C_M . Under this manual control condition effected by the manual control, since one ends of the first and second input impedance circuits II_1 and II_2 are grounded through transfer switches S_2 and S_3 , these grounded terminals are always maintained at the zero potential irrespective of the values of deviation signals ϵ_1 and ϵ_2 supplied by operator sections I and II. For this reason, it is possible to transfer the operation from the manual control to the automatic control by operator section I or operator section II without bumps.

FIG. 24 shows an electrical connection diagram of another embodiment of the novel control which is suitable for use to control an electronic computer or to effect cascade control wherein the set value signal or reference signal varies from time to time. This embodiment comprises a first operator section I which is connected to receive the measured signal e_{M1} from the processing system, a second operator section to which a pulse shaped reference signal E_{SP} is supplied from an electronic computer, for example, and an output section III supplying an output signal to a load L_o . The first operator section I comprises an operational amplifier OA_2 and a feedback circuit for this operational amplifier including a variable resistor R_d for determining the differentiation time constant, a

differentiating capacitor C_d , resistors R_{31} and R_{32} for determining the range of the differentiation operation and resistors R_{21} and R_{22} for controlling the proportionality band. The second operator section II comprises an operational amplifier OA_3 , a feedback capacitor C_o for this operational amplifier, an indicating meter indicating the reference signal ML , a switch S_2 closed by a fault signal S_{AL} impressed upon terminal T_9 and indicating a fault condition of a computer for example, a local setter generally represented by a variable source E_{S1} , an inverter IN for inverting the polarity of the output from the operational amplifier OA_3 and an addition amplifier OA_4 to add the output signal E_s from inverter IN and the measured signal e_{M1} . The third operator section III comprises an operational amplifier OA_1 , a capacitor C_1 and a resistor R_1 comprising the input impedance circuit for the operational amplifier OA_1 , a manual-automatic transfer switch S_1 for transferring the operation between the manual control and the automatic control, a feedback capacitor C_M for operational amplifier OA_1 , and a manual setter MC.

To perform the automatic control, the manual-automatic transfer switch S_1 is thrown to contact SA_1 . Then the measured signal impressed upon input terminals T_1 and T_2 of the first operator section I is subjected to the proportionality gain and differentiating operations effected by operational amplifier OA_2 and its feedback operational circuit. As a result, the output signal e_{M2} from operational amplifier OA_2 is given by equation (14).

$$e_{M2} = e_{M1} \cdot \frac{R_{21} + R_{22}}{R_{22}} \left(\frac{1 + CdRdS}{1 + \frac{R_{31} + R_{32}}{R_{32}} CdRdS} \right) \quad (14)$$

On the other hand the signal impressed across input terminals T_7 and T_8 of the second operational amplifier II , for example a positive or negative pulse train set value signal or a pulse width signal E_{SP} supplied from a computer is converted into an analogue set value signal E_s by the operation of a circuit comprising operational amplifier OA_3 and a capacitor C_o , and the polarity of the signal E_s is then inverted by inverter IN. Operational amplifier OA_4 functions to add the output signal $-E_s$ of inverter IN and the measured signal e_{M1} . Accordingly, the output signal ϵ from the second operator section II is expressed as follows:

$$\epsilon = (R_{21} + R_{22}) / (R_{22}) (e_{M1} - E_s) \quad (15)$$

One input terminal of the operational amplifier OA_1 of the output section III receives the signal e_{M2} as expressed by equation (13) through capacitor C_1 and the signal ϵ as expressed by equation (15) through resistor R_1 . Thus, the output voltage from the output section III, or the output voltage E_o of the controller is expressed by following equation (16).

$$E_o = -e_{M2} \cdot \frac{C_1}{C_M} + \frac{1}{2R_1 C_M S} \cdot \epsilon$$

$$= -e_{M1} \frac{R_{21} + R_{22}}{R_{22}} \left(\frac{1 + CdRdS}{1 + \frac{R_{31} + R_{32}}{R_{32}} \cdot CdRdS} \right)$$

$$+ \frac{1}{2R_1 C_M S} \cdot \frac{R_{21} + R_{22}}{R_{22}} (e_{M1} - E_s) \quad (16)$$

As equation (15) clearly shows, according to this device the measured signal from the processing system is subjected to the proportional and differentiating operations whereas the difference signal ϵ between the measured signal e_{M1} and the set value signal E_s is subjected to the integrating operation alone. For this reason, even when the measured signal varies rapidly, output voltage E_o does not vary rapidly.

During the automatic control operation by the so-called cascade setting effected by a pulse shaped reference signal supplied from a computer and the like, capacitor C_o of the second operator section II always stores an analogue signal

corresponding to the pulse shaped reference signal E_{SP} from the computer. Under these conditions, upon occurrence of a fault of the computer a signal S_{AL} informing the fault will be impressed upon terminal T_9 to throw the switch S_2 to contact S_L . Then the output signal E_S from operational amplifier OA_3 rapidly becomes equal to the voltage of the local setter E_{S1} , but since such a rapid change provides the output voltage by the action of an integrating circuit comprising resistor R_1 , capacitor C_M and operational amplifier OA_1 , so that this output voltage E_o does not vary rapidly.

To provide the manual control operation manual-automatic transfer switch S_1 is thrown to contact S_M whereas the manual control switch S_I or S_D of manual setter MC is closed. Again transfer of the operation between the manual control and the automatic control can be effected without bumps.

While the invention has been shown and described in terms of certain preferred embodiments thereof it is to be understood that the invention is not limited to these particular embodiments and that many changes and modifications will occur to one skilled in the art without departing from the true scope and spirit of the invention as defined in the appended claims.

What is claimed is:

1. A controller comprising an input impedance circuit having an input terminal and an output terminal, means to impress upon said input terminal a signal related to a measured signal from a processing system, an operational amplifier to produce an output signal supplied to a load, a transfer switch connected between the output terminal of said input impedance circuit and the input terminal of said operational amplifier, a feedback circuit including a capacitor connected between input and output terminals of said operational amplifier to store a voltage related to said output signal, and a manual setter including means to modify the voltage stored in said capacitor by an external signal, the arrangement being such that at the time of the automatic control operation said transfer switch is operated to connect said output terminal of said input impedance circuit to said input terminal of said operational amplifier whereas at the time of the control operation by said external signal said transfer switch is operated to disconnect said output terminal of said input impedance circuit from said input terminal of said operational amplifier, thus modifying the voltage stored in said capacitor in said feedback circuit by the signal supplied by said manual setter.

2. The controller according to claim 1 wherein said external signal applied to said manual setter comprises a manually generated signal.

3. The controller according to claim 1 wherein said external signal applied to said manual setter comprises a digital signal supplied from a digital computer.

4. The controller according to claim 1 wherein means is provided to apply a pulse signal to the input terminal of said operational amplifier through a resistor at the time of control by said external signal whereby to modify the voltage stored in said capacitor according to said pulse signal.

5. The controller according to claim 1 which further comprises an output transistor to amplify the output signal from said operational amplifier.

6. The controller according to claim 1 wherein said input impedance circuit comprises a capacitor, means to apply to one terminal of said capacitor said signal related to said measured signal from said processing system, a resistor, and means to apply to one end of said resistor a fraction of said signal related to said measured signal.

7. The controller according to claim 1 wherein said signal related to said measured signal and applied upon said input terminal of said input impedance circuit comprises a different signal between said measured signal and a reference signal.

8. The controller according to claim 1 wherein said signal related to said measured signal and applied to said input terminal of said input impedance circuit comprises a difference signal between a signal obtained by differentiating said measured signal and a reference signal.

9. The controller according to claim 1 wherein said signal related to said measured signal and impressed upon the input terminal of said input impedance circuit comprises a signal obtained by differentiating the difference between said measured signal and a reference signal.

10. The controller according to claim 1 which further comprises a pair of diodes connected in parallel opposition between the input terminal of said operational amplifier and a point of common potential.

11. A controller comprising an input impedance circuit having an input terminal, means to impress upon said input terminal a signal related to a measured signal from a processing system, an operational amplifier to produce an output signal supplied to a load, a holding capacitor with one terminal connected to the output terminal of said operational amplifier to store a voltage corresponding to said output signal, a feedback circuit including said holding capacitor and connected between the input and output terminals of said operational amplifier, a transfer switch connected between the output terminal

15 of said input impedance circuit and the input terminal of said operational amplifier, and a manual setter including means to modify the voltage stored in said holding circuit, said transfer switch being operable to connect the output terminal of said input impedance circuit to the input terminal of said operational amplifier and to connect the other end of said holding capacitor to a point of common potential during the automatic control operation, whereas during the controlling operation by an external signal said transfer switch operating to connect the output terminal of said input impedance circuit to said point of common potential and to connect one terminal of said holding capacitor to the input terminal of said operational amplifier.

20 12. The controller according to claim 1 which further comprises a limiter circuit connected to the output terminal of said operational amplifier, and wherein the upper and lower limit set values of said limiter circuit are variable.

25 13. The controller according to claim 1 wherein said limiter circuit is provided with means for setting said upper and lower limit values to substantially the same value to manually vary said values in union to adjust the output signal supplied to said load.

30 14. The controller according to claim 12 wherein said limiter circuit comprises a variable resistor having two sliding brushes, a first transistor rendered ON and OFF in accordance with the relative magnitude between the voltage produced at one brush of said variable resistor and the voltage impressed upon the input terminal of said limiter circuit, a second transistor rendered ON and OFF by said first transistor, and a third transistor rendered ON and OFF in accordance with the relative magnitude between the voltage produced at the other brush and at the input terminal of said limiter circuit.

35 15. The controller according to claim 12 wherein said limiter circuit comprises a variable resistor having two brushes, a first comparator supplied with the voltage produced at one of said brushes and voltage related to the output voltage supplied to said load, a first diode rendered ON and OFF by the output from said comparator, a second comparator supplied with the voltage produced at the other of said brushes and a voltage related to said output voltage supplied to said load, and a second diode rendered ON and OFF in accordance with the output from said second comparator.

40 16. The controller according to claim 1 which further comprises a source of supply to energize said operational amplifier and means to shift the voltage levels of the input and output signal of said operational amplifier by a definite voltage.

45 17. A controller device comprising a primary controller including a first input impedance circuit having an input terminal and an output terminal, means to impress upon said input terminal a signal related to a measured signal from a processing system, a first operational amplifier to produce an output signal a local setter, a cascade-local transfer switch connected between the output terminal of said input impedance circuit and the input terminal of said operational am-

50

plifier for switching the operation between the control by cascade setting and the control by said local setter, a feedback capacitor for said operational amplifier connected to store a voltage related to the output voltage from said operational amplifier, said local setter including means to modify the voltage stored in said capacitor; and a second controller comprising a second input impedance circuit including a second capacitor, means to apply to the input terminal of said second input impedance circuit a signal related to the difference between a signal related to a second measured signal from a processing system and the output signal from said primary controller, a second operational amplifier, a second transfer switch interposed between the output terminal of said input impedance circuit and the input terminal of said second operational amplifier, a feedback circuit for said second operational amplifier including a third capacitor to store a voltage related to the output signal supplied to a load from said second operational amplifier and a manual setter including means to modify the voltage stored in said third capacitor in accordance with an external signal, said second controller being connected to utilize said output signal from said first controller as the set value signal.

18. The controller device according to claim 17 wherein said local setter comprises a voltage generator, an operational amplifier and a balancing motor, the arrangement being such that during the control operation by cascade setting, said voltage generator, said operational amplifier and said balancing motor constitute a servo circuit whereas during the control operation by local setting constitute a circuit to send out the voltage generated by said voltage generator.

19. The controller device according to claim 17 wherein said local setter comprises a voltage generator having a local setting controlling means to adjust the voltage generated by said voltage generator.

20. The controller according to claim 1 which further comprises means to apply to the input terminal of said operational amplifier a feed forward signal through a capacitor.

21. A controller comprising an operational circuit connected to receive a measured signal from a processing system for obtaining a deviation signal between said measured signal and a reference signal, a feed forward signal generating circuit to add an external disturbance signal and the output signal from said operational circuit, and at least one output section including an operational amplifier to supply an output signal to a load, a transfer switch provided on the input side of said operational amplifier, a feedback circuit for said operational amplifier to store a voltage related to said output signal, and a manual setter including means to modify the voltage stored in said capacitor in accordance with an external signal, the arrangement being such that during the automatic control operation the output signal of said operational circuit is supplied to the input terminal of said operational amplifier of said output section via a resistor and the output signal from said feed forward signal generating circuit is supplied to the input terminal of said operational amplifier whereas during the controlling operation by said external signal opposite terminals of said resistor and said capacitor are connected to a point of common potential.

22. An automatic selecting controller device comprising at least two controllers, each of said controllers comprising an input impedance circuit connected to receive at its one terminal a signal related to a measured signal from a processing system, an operational amplifier, a transfer switch interposed between the end of said input impedance circuit and the input terminal of said operational amplifier, a feedback capacitor for said operational amplifier, and a manual setter including

means to modify the voltage stored in said capacitor in accordance with an external signal; an automatic selector circuit including a diode; means to apply output signals from said at least two controllers whereby to supply an output signal corresponding to a larger or smaller one of said output signals to a load; and means to store a voltage related to said output signal supplied to said load in said feedback capacitor.

23. The automatic selecting controlling device according to claim 22 wherein said automatic selector circuit includes a transistor with its emitter electrode connected to a source of supply.

24. The automatic selecting controlling device according to claim 22 wherein said automatic selector circuit includes a transistor with its collector electrode connected to a source of supply.

25. A controller device comprising at least two controllers, each of said adjusters including an input impedance connected to receive at its input terminal a signal related to a measured signal from a processing system, an operational amplifier, a transfer switch disposed between the output terminal of said input impedance circuit and the input terminal of said operational amplifier, a feedback capacitor for said operational amplifier, and a manual setter including means to modify the voltage stored in said capacitor; a load; a second transfer switch to selectively supply the outputs from said at least two controllers to said load; and means to store in said feedback capacitor a voltage related to the output signal supplied to said load.

26. A controller comprising at least two operator sections to determine the difference between a measured signal from a processing system and a reference signal, at least two input impedance circuits each including a capacitor and connected to receive at its one terminal a signal related to the output signal from one of said operator sections, an operational amplifier, a transfer switch interposed between the other terminals of said input impedance circuits and the input terminal of said operational amplifier, a feedback capacitor for said operational amplifier to store a voltage related to the output signal supplied to a load from said operational amplifier, and a manual setter including means to modify the voltage stored in said feedback capacitor in accordance with an external signal, the arrangement being such that during the automatic control operation said transfer switch operates to connect the output terminal of either one of said at least two input impedance circuits to the input terminal of said operational amplifier whereas during the manual control operation said transfer switch operates to connect the output terminals of said input impedance circuits to a point of common potential.

27. A controller comprising a first operator section connected to receive a measured signal from a processing system to subject said measured signal at least to a proportionality gain operation, a second operator section to determine the difference between a reference signal and said measured signal, an operational amplifier to supply an output signal to a load, a transfer switch connected to the input terminal of said operational amplifier, a feedback capacitor for said operational amplifier to store a voltage related to said output signal, and a manual setter including to modify the voltage stored in said feedback capacitor in accordance with said external signal, the arrangement being such that said transfer switch operates to apply the output voltage from said first operator section to the input terminal of said operational amplifier during the automatic control operation whereas during the control operation by said external signal said transfer switch operates to connect the output terminal of said first operator section to a point of common potential through a capacitor.
